WINDOW WITH REMOVABLE SASHES
Carl A. Niese, Seattle, Wash., assignor to Zephyr Aluminum Company, Seattle, Wash., a corporation of Washington

Filed Sept. 15, 1961, Ser. No. 138,459
9 Claims. (Cl. 20—52.2)

The present invention relates to prefabricated windows of the general type having removable sashes which slide between open and closed positions.

It is a principal object of the invention to provide such a window which may be used to replace a conventional double-hung window with minimum of labor performed from inside the building structure and without disturbing the indoor and outdoor wall surfaces, the outside moulding, or the inside casing.

A further object is to provide a storm window with sliding sashes which can be easily removed and cleaned from indoors.

Another object is to provide a window which will not only perform the above objects, but is weather tight, pleasing in appearance, and of simple and economical construction.

Other more particular objects and advantages of the invention will, with the foregoing, appear and be understood in the course of the following description and claims, the invention consisting in the novel construction and in the adaptation and combination of parts hereinafter described and claimed.

In the accompanying drawings:

FIGURE 1 is a top plan view in section showing a conventional double-hung window installation.

FIG. 2 is a view taken similar to that of FIG. 1 in which the double-hung window of FIG. 1 has been replaced by a window unit embodying the teachings of the present invention.

FIG. 3 is an elevational view, with parts broken away, of the window frame of the present invention, with the sashes removed and as seen from an indoor position.

FIG. 4 is a vertical sectional view taken on line 4—4 of FIG. 3, the closed positions of the sashes being shown in broken line.

FIG. 5 is a horizontal sectional view taken on line 5—5 of FIG. 3, and with the extreme outdoor sash shown in operating position by full lines and in the various stages of the removal process by broken lines.

FIG. 6 is a fragmentary front elevational view of the window, showing the extreme indoor sash by full and broken lines in various stages of the installation process, but without illustrating the sash bolts.

FIG. 7 is a fragmentary front elevational view partly in vertical section of a sash made in accordance with the present invention and showing part of the related border frame in phantom.

FIG. 8 is a side elevational view taken on line 8—8 of FIG. 7.

FIG. 9 is a bottom detail view taken from the vantage indicated at 9—9 in FIG. 7; and

FIG. 10 is a transverse detail sectional view taken on line 10—10 of FIG. 7.

Referring to the drawings of the present invention it is seen that the window of the present invention has a rectangular border frame assembly which slidably receives four removable sashes, and namely, a set of upper and lower outdoor sashes 11—12, and a set of upper and lower indoor sashes 13—14. In cross-section the border frame is generally channel shaped, the web of the channel being formed by a frame bar 15 and the flanges of the channel comprising pairs of outdoor and indoor track forming bars which are designated 16a—17a at

2

the head, 16b—17b at the two sides, and 16c—17c at the foot. Each of these track bars has an outer leg 18 which fits with a vinyl gasket 20 into the groove of respective outdoor and indoor channel portions 21—22 of the frame bar 15. The web portion between these channel portions is numbered 23 and the frame bar is completed by an indoor trim flange 24 spaced indoors of the channel portion 22 by a web extension 25. The trim flange 24 projects outwardly at 26 relative to the web extension as a support leg and this leg is complemented at the outdoor face by a leg 27 which is a continuation of the outdoor flange of the channel portion 21. At the sill, this outdoor support leg 27 is extended as indicated at 27a and slidably receives an expander 28 of channel configuration having a sloped sill engaging base 28a.

Returning to the track forming bars, it is seen that each has an inwardly faced indoor channel continuing from its outer leg 18 and also has an outdoor channel 20 stepped inwardly from the indoor channel as a continuation of the outdoor flange of the latter. More specifically in the case of the head track bars 16a—17a the outdoor channels are marked 30a—31a while the indoor channels are designated 32a—33a. The corresponding channels of the track bars at the sides and foot are given like identification but with B and C letter suffixes, respectively. Directing attention to FIGS. 4—5 it will be noted that the track channels 30b—31b at the sides of the window have their indoor flange shortened and are narrowed at the mouth by sash guide flanges 34. Similarly, sash guide flanges 35 are provided for the side track channels 32b—33b. The indoor flanges of the track channels 30c—31c are also shortened and they have stop flanges 36 stepped below their upper edges to serve as a sash seat. Likewise, stop flanges 37 are provided on the indoor flanges of the foot track channels 32c—33c.

The four sashes 11—14 are of the same general construction, such being shown in FIGS. 7—10. At its upper corners each sash presents oppositely projecting horizontal fingers 40—40 which are rigid extensions of angle pieces 41. These angle pieces fit by their legs within like head and side frame bars 42 and 43—43, respectively, which are mitered at the corners and are coined at 44 into dimples 45 in the opposite faces of the angle pieces. A second pair of angle pieces 46, minus the fingers 40, similarly join the side bars 43 to a foot bar 47.

A pair of retractable bolts 48—48 of a general Z-shape in elevation are guided in a depending track portion 47a in the foot bar 47 to complement the fingers 40. These bolts are projected outwardly by compression springs 50 which bear against their inner ends and are housed and anchored on tabs 49 opposite the lower legs of the angle pieces 46. The free ends of these lower legs serve as stops for the jog shoulders 51 to retain the bolts. Depending handles 52 are provided near the inner ends of the bolts while at their outer ends the bolts have a tongue portion 53 and a key 54 which projects therefrom in the indoor direction and has a tapered end face 54a. Access to the handles 52 is aided by cutouts 55 in the bottom flange of the track portion 47a. The glass pane 56 for each sash is retained and sealed by vinyl glazing beads 57 which are forced between the edge of the pane and a beveled tongue 58 provided by the frame bars of the sash.

The indoor flanges of the track channels 30b—30b and 32b—32b at both sides of the window are formed with intermediate notches 62—62 and bottom notches 63—63, respectively, for receiving the keys 54 of the bolts 48 at the lower ends of the sashes 11—12 to thereby lock the sashes. Also, as seen in FIGS. 3 and 5, the indoor flanges of the track channels 30b and 32b at one side of

the window have horizontally aligned slots 60 and 61, respectively, such being shown on the right hand side as viewed from indoors for purposes of example. When the sashes 11-12 are in operating position in the window their fingers 40 and bolt tongues 53 are guided in the track channels 30b-30b and 32b-32b. In their closed position, illustrated in FIG. 4, the head of sash 11 nests in the channel 30a while the foot of sash 12 seats in the channel 32c on the related stop 37. The sashes 11-12 are locked in this closed position by action of their bolt keys 54 fitting in the respective notches 62-63. One or more additional pairs of notches 64 is provided in the indoor flanges of the side flanges 32b-32b above the bottom notches 63 to receive the bolt keys of sash 12 so that they will hold the sash open when such is desired.

Directing attention to FIG. 5, it can be seen how the outdoor sashes 11-12 are removed for cleaning. Using sash 11 for example, and assuming that the other sashes have been removed, the sash is first lowered to bring the right hand of its fingers 40 into registration with the slot 60. Then, after retracting the bolts 43, the sash is skewed indoors about its left hand finger to Position A from which the sash is moved both indoors and to the right so that its right hand portion enters the trough defined by the respective track forming bars 16b-17b as indicated by Position B. The sash is then skewed to bring the left hand side through the opening defined by the indoor track bars as illustrated by Position C whereupon the sash may be moved indoors free of the window frame. Installation of the sash is readily performed by reversing this removal sequence.

Referring now to FIG. 6, to insert the indoor sashes 13-14, and using sash 14 for example, the sash is held with the plane thereof generally horizontal with the end having the fingers 40 adjacent the window frame. Then the sash is cocked and moved in the outdoor direction until its fingers 40 are in the plane of the track channels 33b whereupon the sash is shifted laterally slightly to introduce the finger at the lower of the two side edges into the adjacent track. At this point the sash is in the full line position of FIG. 6. Dropping the raised side edge back to the horizontal as indicated by the broken line position in FIG. 6 introduces the other fingers in its related track. Then, with the bolts retracted, the bolt end of the sash is swung downwardly to the vertical about the fingers 42 as a pivot axis and the bolts are released to introduce their tongues 53 in the tracks 33b together with the fingers. The sash is removed by reversing this procedure.

Sets of notches are also provided in the indoor flanges of the track channels 31b, 33b to receive the bolt keys 54 of the indoor sashes 13-14 so that they can be selectively locked in closed and open positions. More particularly, notches 65 and 66 give the respective lock positions for sashes 13 and 14, respectively, and slots 67a, b and c give various open positions for the sash 14. Indirect ventilation can be provided by lowering the upper indoor pane 13 and raising the lower outdoor pane 12. If desired, a screen, indicated at 68 in FIG. 4, may be provided with the same finger and bolt arrangement as the sashes and introduced in like manner after installation of the sash 11. For this purpose a second slot 68a is provided.

It should be understood that the various slots for registering with the fingers 42 are purposely located or dimensioned such that the portion of the bolt tongues 53 outward of the related key 54 cannot pass therethrough. Likewise, the fingers 42 cannot pass through the notches for the bolt keys 54. With this arrangement there is no danger of accidentally partially removing one of the sashes while sliding it up or down.

When the sashes are in their closed positions there is some overlap therebetween as shown in FIG. 4. It is preferred that these overlapping portions have interfitting beads 69a, 69b. It is also preferred that the outdoor

faces of the sash frames be provided with weather stripping to engage the outdoor flanges of the related track channels.

In FIG. 1 there is illustrated a conventional double-hung wood window for a rough opening defined by a beader, jambs 70-70, and a sloped sill 71 having a stool 75. The outdoor sash 73 of the window is held between a blind stop 72 and parting stop 76, and has its indoor sash 74 retained by the parting stop and a trim stop 77. To replace the window 73-74 by that of the present invention it is only necessary after cutting the sash cords to remove the trim stop 77, lift out the indoor sash 74, remove the parting stop 76, lift out the outdoor sash, insert the new window frame from indoors, screw the web 23 to the jamb at 78 (see FIG. 2), nail back the trim stop 77, and insert the sashes 11-14. The slope of the sill 71 is taken up by adjusting the expander 28 so that its base 28a bears against the sill. Each of these steps can be readily performed from inside the building structure.

When the sashes 11-12 are closed they function as a storm unit to confine a dead air space to the outdoors of the sashes 13-14. Yet, they can be easily opened for ventilation and readily removed from inside for cleaning. Furthermore, a screen can be simply installed and removed.

It will be noted that the invention particularly lends itself to the use of extruded aluminum shapes in which case the corners of the border frame assembly may have their mitered components secured together in any suitable manner as by welding, stapling or screws.

It is believed that the invention will have been clearly understood from the foregoing detailed description of my now-preferred illustrated embodiment. Changes in the details of construction may be resorted to without departing from the spirit of the invention and it is accordingly my intention that no limitations be implied and that the hereto annexed claims be given the broadest interpretation to which the employed language fairly admits.

What I claim is:

1. A window comprising a rectangular border frame having opposite sides with a generally channel-like cross-section providing spaced indoor and outdoor flanges, said outdoor flange presenting a pair of groove tracks facing toward the center of the frame, an outdoor pair of overlapping rectangular sashes for said tracks of said outdoor flange and each being wider between said tracks than the corresponding width of the opening surrounded by said indoor flange, each of said sashes presenting oppositely projecting fingers near one of its ends and a retractable bolt near the other of its ends riding in the respective track for the sash, each of said outdoor sashes being thinner than the space between said indoor and outdoor flanges and the indoor walls of the tracks of said outdoor flange at one of said opposite sides each having a through slot for the passage of a respective said finger whereby said pair of outdoor sashes can be consecutively skewed into the space between said indoor and outdoor flanges adjacent said slots and then skewed between said indoor flanges to completely free them from the border frame.

2. A window comprising a rectangular border frame having a generally channel-like cross-section providing spaced continuous indoor and outdoor flanges, said outdoor flange presenting a pair of groove tracks facing toward the center of the frame at opposite sides, an outdoor pair of overlapping rectangular sashes for said tracks of said outdoor flange, each of said sashes presenting oppositely projecting fingers near one of its ends and a retractable bolt near the other of its ends riding in the respective track for the sash, the inside perimeter of said outdoor flange being as large as the inside perimeter of said indoor flange, each of said outdoor sashes being thinner than the space between said indoor and outdoor flanges and the indoor walls of the tracks of said outdoor flange at one of said opposite sides each having a through

slot for the passage of a respective said finger whereby said pair of outdoor sashes can be consecutively skewed into the space between said indoor and outdoor flanges adjacent said slots and then skewed between said indoor flanges to completely free them from the border frame.

3. A window comprising a rectangular border frame having opposite sides with a generally channel-like cross-section providing spaced indoor and outdoor flanges, said outdoor flange presenting a pair of groove tracks facing toward the center of the frame, an outdoor pair of overlapping rectangular sashes for said tracks of said outdoor flange and each being wider between said tracks than the corresponding width of the opening surrounded by said indoor flange, each of said sashes presenting oppositely projecting fingers near one of its ends and a retractable bolt near the other of its ends riding in the respective track for the sash, said bolts each having a key spaced from the outer free end thereof, each of said outdoor sashes being thinner than the space between said indoor and outdoor flanges and the indoor walls of the tracks of said outdoor flange at one of said opposite sides each having a through slot for the passage of a respective said finger whereby said pair of outdoor sashes can be consecutively skewed into the space between said indoor and outdoor flanges adjacent said slots and then skewed between said indoor flanges to completely free them from the border frame, and the indoor walls of the tracks of said outdoor flange at one of said opposite sides each having a notch to receive one of said keys for locking the respective sash.

4. A window comprising a rectangular border frame having opposite sides with a generally channel-like cross-section providing spaced indoor and outdoor flanges each of which flanges presents a respective pair of groove tracks facing toward the center of the frame, an outdoor pair of overlapping rectangular sashes for said tracks of said outdoor flange and each being wider between said tracks than the corresponding width of the opening surrounded by said indoor flange, and an indoor pair of overlapping removable rectangular sashes for said tracks of said indoor flange, each of said sashes presenting oppositely projecting fingers near one of its ends and retractable bolts near the other of its ends riding in the respective track for the sash, each of said outdoor sashes being thinner than the space between said indoor and outdoor flanges and the indoor walls of the tracks of said outdoor flange at one of said opposite sides each having a through slot for the passage of a respective said finger whereby said pair of outdoor sashes can be consecutively skewed into the space between said indoor and outdoor flanges adjacent said slots and then skewed between said indoor flanges to completely free them from the border frame after removal of said pair of indoor sashes.

5. A window comprising a rectangular border frame having a generally channel-like cross-section providing spaced continuous indoor and outdoor flanges, said outdoor flange presenting a pair of groove tracks facing toward the center of the frame, the outdoor groove track of said pair being spaced toward the center of the window from the other groove track, an outdoor pair of overlapping rectangular sashes for said tracks of said outdoor flange and each being wider between said tracks than the corresponding width of the opening surrounded by said indoor flange, each of said sashes presenting oppositely projecting fingers near one of its ends and a retractable bolt near the other of its ends riding in the respective track for the sash, each of said outdoor sashes being thinner than the space between said indoor and outdoor flanges and the indoor walls of the tracks of

said outdoor flange at one side of the window each having a through slot for the passage of a respective said finger whereby said pair of outdoor sashes can be consecutively skewed into the space between said indoor and outdoor flanges adjacent said slots and then skewed between said indoor flanges to completely free them from the border frame.

6. A window comprising a rectangular border frame having a generally channel-like cross-section providing spaced continuous indoor and outdoor flanges each of which flanges presents a respective pair of continuous groove tracks facing toward the center of the frame, the outdoor groove of each said pair being spaced toward the center of the window from the other groove track of the respective pair, an outdoor pair of overlapping rectangular sashes for said tracks of said outdoor flange and each being wider between said tracks than the corresponding width of the opening surrounded by said indoor flange, and an indoor pair of overlapping removable rectangular sashes for said tracks of said indoor flange, each of said sashes presenting oppositely projecting fingers near one of its ends and retractable bolts near the other of its ends riding in the respective track for the sash, each of said outdoor sashes being thinner than the space between said indoor and outdoor flanges and the indoor walls of the tracks of said outdoor flange each having a through slot for the passage of a respective said finger whereby said pair of outdoor sashes can be consecutively skewed into the space between said indoor and outdoor flanges adjacent said slots and then skewed between said indoor flanges to completely free them from the border frame after removal of said pair of indoor sashes.

7. The window of claim 6 in which said bolts have locking keys and in which said groove tracks have notches therein facing toward the center of the window and arranged to receive respective of said keys to lock said sashes in positions closing the window.

8. The window of claim 7 in which said fingers cannot pass through said notches and said bolts cannot pass through said slots.

9. A window comprising a rectangular border frame having a generally channel-like cross-section providing spaced continuous indoor and outdoor flanges, said outdoor flange presenting a pair of groove tracks facing toward the center of the frame at opposite sides, an outdoor pair of overlapping rectangular sashes for said tracks of said outdoor flange and each being wider between said tracks than the corresponding width of the opening surrounded by said indoor flange, each of said sashes presenting oppositely projecting fingers near one of its ends and a retractable bolt near the other of its ends riding in the respective track for the sash, each of said outdoor sashes being thinner than the space between said indoor and outdoor flanges and the indoor walls of the tracks of said outdoor flange at one of said opposite sides each having a through slot for the passage of a respective said finger whereby said pair of outdoor sashes can be consecutively skewed into the space between said indoor and outdoor flanges adjacent said slots and then skewed between said indoor flanges to completely free them from the border frame, said slots being located out of the travel range of said bolts.
